[57] ABSTRACT

A horizontal scrubbing brush for a vehicle-washing apparatus is vertically guided on a support which is pivotally mounted on a portal frame for swinging about a horizontal axis, on either side of a normal vertical position, whenever the brush is deflected by contact with a transverse vehicular surface. If the swing exceeds a predetermined angle of inclination, a hoist motor is operated by an inclination-sensing switch to raise the rotating brush until the latter has returned to substantially its normal position, the weight of the brush being partly counterbalanced so that the brush bears under light pressure upon an adjoining generally horizontal vehicle surface after the hoist motor has been stopped. Another motor, controlled by the same switch, operated during standstill of the hoist motor to advance the portal frame with reference to the vehicle (or vice versa) to let the brush sweep the last-mentioned surface.

CONTROL MECHANISM FOR HORIZONTAL VEHICLE-SCRUBBING BRUSH

My present invention relates to a plant for cleaning, i.e., washing and/or drying, automotive vehicles and the like with the aid of rotating scrubbing brushes, e.g., as generally described in my prior U.S. Pat. No. 3,500,487.

Such systems normally include a so-called portal frame which straddles the path of the vehicle to be cleaned and which carries one or more scrubbing brushes, including at least one brush rotatable about a horizontal axis for cleaning the front, top and rear surfaces of the vehicle. Motion is imparted to the frame and/or to the vehicle for relatively displacing same during the scrubbing operation, the drive means used for this purpose being advantageously reversible to permit a more intensive sweep of both end surfaces.

While the front and rear surfaces of any automotive vehicles may be regarded generally as vertical, they do vary in shape and orientation from one vehicle to another, being usually somewhat inclined and gently curved in passenger cars but relatively steep and sharp-edged in trucks or the like. With the usual hoisting equipment associated with such horizontal scrubbing brushes, the rate of ascent of the brush along these transverse surfaces depends on the frictional resistance encountered and is therefore a function of the angle of inclination as well as of other structural aspects of such surfaces. The application of a given lifting force to the brush may therefore result in a faster or slower upward movement, at a rate which in some cases may unduly retard the completion of the scrubbing cycle and in other cases may excessively accelerate it at the expense of reduced efficacy.

Furthermore, experience has shown that the greatest scrubbing efficiency is attained if the brush is set in counterrotating motion, i.e., if its sense of rotation is such as to oppose any upward movement of the brush along a vertical surface scrubbed thereby. In conventional scrubbing systems, however, such a sense of rotation is frequently impractical since it increases the frictional resistance encountered by the brush and may, under certain circumstances, completely halt its ascent. With the brush rotating in the opposite (forward) direction, the brush tends to creep up on the engaged surface so that the duration of the sweep and the relative velocity of the bristles along the surface are both diminished with resulting reduction of the scrubbing effect.

The general object of my present invention, therefore, is to provide an improved control mechanism for the relative movement of a vehicle and a scrubbing brush to afford an adequate treatment time for the end and top surfaces of a vehicle to be washed or dried, regardless of the shape and angle of inclination of the surfaces, with proper correlation between the vertical and horizontal motions.

A more specific object is to provide a system enabling the realization of the aforesaid advantage with a counterrotating brush.

In accordance with the present invention, I provide a mounting for a horizontal scrubbing brush which biases the same downwardly onto an underlying vehicle surface in the unoperated condition of an associated hoist motor, this motor being turned on or off by a position

sensor responsive to a deflection of a swingable brush support on the portal frame from a general vertical normal position. In that normal position, the sensor actuates the main drive motor to displace the vehicle with reference to the frame, or vice versa, along the track; under these circumstances the brush is suspended in its bottom position or bears under light pressure upon an underlying vehicle surface. In the off-normal position of the brush support, i.e., when the latter has been swung out by a predetermined angle, the previously deactivated hoist motor is operated to elevate the brush until it clears the vehicular end surface by which it had been deflected. Thereafter, as the support returns to normal, the hoist motor stops and the brush rides — preferably under its own, partly counterbalanced weight — on an adjoining, generally horizontal surface such as the hood or the roof of the vehicle. On reaching the opposite end surface, the brush drops down to its bottom level while the main drive is arrested and preferably reversed, manually or automatically, to repeat the process in the other direction.

According to a more specific feature of my invention, the main drive is arrested whenever the hoist motor is energized so that no relative horizontal movements between the portal frame and the vehicle occurs while the brush is being elevated. If, during the sweep of a rising surface, the brush support is restored to its normal position because of a substantial inclination of that surface toward the vertical, the main drive is restarted and the hoist motor is arrested to hold the brush level constant while the portal frame advances to take up the slack. The swingable brush support may be provided with centering springs or the like tending to maintain it in its normal vertical position.

The above and other features of my invention will be described hereinafter with reference to the accompanying drawing in which:

FIG. 1 is a somewhat diagrammatic cross-sectional view of a portal frame provided with a swingable brush support according to the present invention;

FIG. 2 is a diagram of the control circuit for the several motors of the assembly of FIG. 1; and

FIGS. 3A-3L are a set of diagrammatic view illustrating the mode of operation of the system.

In FIG. 1 I have shown a horizontal scrubbing brush 1 for washing the front, top and rear surfaces of an automotive vehicle V passing through a portal frame 4. This frame is horizontally displaceable on a pair of rails 5 (only one shown) on which it rides by means of wheels 6 driven, in either of two directions, by a reversible electric motor 12. Another electric motor 11 drives a capstan 11' around which a cable 3 is wound a few times, this cable passing about a pair of deflecting rollers 3', 3'' and engaging one end of the shaft 1' of brush 1 whose other end is similarly suspended from a second cable not shown. The two shaft ends are guided in slots 8' of a pair of uprights 8 (only one shown) which are swingable about the axis of roller 3' at opposite sides of frame 4. A counterweight 9 at the free end of cable 3, together with a similar counterweight at the corresponding and of the second cable, partly balances the weight of brush 1 so that the same, in the de-energized state of motor 11, will tend to descend slowly to its bottom position as the capstan 11' is decoupled from the motor shaft by the concurrent

release of, say, an electromagnetic clutch (not shown) energized jointly with the motor. When operated, motor 11 rotates in a direction tending to raise the brush 1 toward the top of frames 4. A limit switch, not shown, may stop the motor 11 at that point.

In accordance with an important feature of my invention, brush support 8 carries a sensing device 10 which has been shown as a mercury switch but which could also be in the form of a photocell, a set of mechanical contacts or the like. Sensor 10 detects any major deviation of brush support 8 from its illustrated normal position, i.e., a swing thereof to either side by a predetermined angle $+\alpha$ or $-\alpha$. Another switch 13 on support 8 is tripped by a dog 14, adjustably carried on cable 3, whenever the brush passes a predetermined level well above the top of the tallest vehicle to be scrubbed.

FIG. 2 illustrates, in addition, a manual master switch 15 in series with a source of operating current, a reversing switch 16 in the operating circuit of motor 12, a similar switch 16' (ganged with switch 16) in the operating circuit of a further motor 17 reversibly driving the shaft 1' of brush 1, a relay 18 operated in the closed state of switches 13 and 15, and a pair of alternately opened and closed switches 2, 2' in series with two off-normal bank contacts of position sensor 10. Switch 13 is closed whenever brush 1 is elevated above the aforescribed level from which, in the unoperated state of hoist motor 11, it can descend under its own weight to the bottom of frame 4 (FIG. 1). Upon such descent, switch 13 is opened so that relay 18 cannot be energized, even if switch 15 is closed, as long as sensor 10 is in its normal position engaging its center contact. In that position, however, the main drive motor 12 is operated, in a direction determined by the position of reversing switch 16, in parallel with brush motor 17 whose sense of rotation is determined by the position of reversing switch 16' positively coupled with switch 16. In the illustrated position of switches 16 and 16', switch 2 is open while switch 2' is closed so that relay 18 can be energized only if the armature of sensor 10 engages its right-hand bank contact in series with that switch, i.e., if the brush support 8 is deflected by the angle $+\alpha$ (FIG. 1) into one of its two off-normal positions. When this occurs, relay 18 re-energizes the hoist motor 11 while the circuit of main drive motor 12 is interrupted at circuit breaker 10. If the switches 16 and 16' had been in their alternate position, motor 11 would have been energized only upon a deflection of the brush by an angle $-\alpha$ in the opposite direction, with the armature of sensor 10 engaging its left-hand bank contact.

I shall now describe, with reference to FIGS. 3A-3L, successive stages in the scrubbing of a vehicle V by the system shown in FIGS. 1 and 2.

In these figures, an arrow W indicates one direction of displacement of portal frame 4 (FIG. 1) relative to vehicle V, the opposite sense of displacement being denoted by an arrow W'. Arrows X and X' show the two senses of rotation of brush 1 corresponding to the directions of movement W and W', respectively. An arrow Y indicates the descent of brush 1 under its own weight, whereas an arrow Z shows its elevation by means of the hoist motor 11 (FIGS. 1 and 2).

Switches 2 and 2' have been indicated diagrammatically in FIGS. 3A-3L by a pair of circles. An empty circle represents the inactive state of the switch (as shown for switch 2 in FIG. 2); a cross in the circle signifies a switch that is active but open-circuited (switch 2' in FIG. 2) whereas a dot in the circle denotes a switch that is both active and in circuit (engagement of the corresponding bank contact of sensor 10).

Thus, FIG. 3A shows the condition of brush 1 rotating counterclockwise (arrow X) and moving horizontally toward the front of the vehicle (arrow W). Switch 2' is enabled but, at this instant, open-circuited so that the hoist motor is not operated, brush 1 therefore remaining at its illustrated bottom level. This condition is not changed as the brush contacts the front of the vehicle, FIG. 3B, until the continuing advance of the portal frame deflects the brush and its support by the requisite angle $-\alpha$ (FIG. 1) as shown in FIG. 3C. At this point the switch 2' completes the circuit for the hoist motor whose operation is symbolized by the arrow Z. With continuing counterclockwise rotation, the brush now scrubs the radiator grill of the vehicle (FIG. 3D) without continuing on its horizontal path since the drive motor 12 (FIGS. 1 and 2) has been stopped. As the spring reaches the top of the hood, FIG. 3E, its normal vertical position is restored by its own weight and/or by the force of centering springs (not shown) on the frame engaging the support 9 from opposite sides. With sensor 10 returned to its neutral position, the hoist motor is stopped while the frame drive is resumed so that the brush slowly sweeps the top of the hood without substantial upward movement; if, however, the surface were so rough or so steep as to retard the horizontal advance of the brush to a significant extent, the hoist motor would be briefly reoperated to raise the brush slightly with momentary interruption of the rearward sweep. Next, as shown in FIG. 3F, the brush is again deflected by its engagement with the windshield so that hoist motor 11 and drive motor 12 are alternately energized whereby the brush rides up that sloping surface in a stepped motion which, however, results in a continuous sweep owing to the resiliency of its bristles. On reaching the roof of the car, FIG. 3G, the brush resumes its steady rearward movement (arrow W) without any further energization of the hoist motor, descending under its own weight along the rear surface of the vehicle as indicated by arrow Y in FIG. 3H.

Subsequently, as suggested by arrows W' and X' in FIG. 3I, the sense of horizontal movement and brush rotation is reversed with simultaneous activation of switch 2 in lieu of switch 2'. FIG. 3J shows the reverse swing of the brush, by an angle $-\alpha$ (FIG. 1), as the brush re-engages the transverse rear surface of the vehicle at the beginning of its forward stroke. This deflection stops the forward drive and reoperates the hoist motor (arrow Z) whereupon the trunk and the rear window of the car are scrubbed essentially in the manner described with reference to the hood and the windshield. The roof of the car is swept once more (FIG. 3K), with the brush moving in the forward direction W', followed by a descent of the brush along the windshield and the hood to its starting level as shown in FIG. 3L.

It should be understood that the electric hoist motor 11 and other parts of the system may be replaced, if

desired, by equivalent hydraulic and/or pneumatic means, e.g., as described in my above-identified prior U.S. Pat. No. 3,500,487.

I claim:

1. In a vehicle-cleaning plant comprising a portal frame straddling the path of a vehicle to be treated, first drive means for relatively displacing said frame and said vehicle, a scrubbing brush on said frame rotatable about a horizontal axis, second drive means for rotating said brush, and hoist means for raising said brush with reference to said path, the combination therewith of a support for said brush pivotally mounted on said frame for swinging about a horizontal axis, sensing means responsive to a swinging of said support by a predetermined angle into an off-normal position from a substantially vertical normal position, and circuit means controlled by said sensing means for operating said first drive means to the exclusion of said hoist means in said substantially vertical normal position and for operating said hoist means in said off-normal position with continuous operation of said second drive means, said brush being downwardly biased for descending onto an underlying vehicle surface in the unoperated state of said hoist means.

2. The combination defined in claim 1 wherein said first drive means is reversible, said support being swingable into two alternate off-normal positions on opposite sides of said substantially vertical normal position, said sensing means being responsive to a swinging

5

10

15

20

of said support into either of said alternate off-normal positions for arresting said first drive means and operating said hoist means.

3. The combination defined in claim 2 wherein said second drive means is also reversible, further comprising control means for simultaneously reversing both said drive means for rotating said brush always in a sense tending to lower the latter upon scrubbing a vertical vehicle surface.

4. The combination defined in claim 3 wherein said circuit means comprises a pair of switches coupled to said control means for completing an operating circuit for said hoist means in either of said alternate off-normal positions upon rotation of said first and second drive means in a first and a second direction, respectively.

5. The combination defined in claim 1 wherein said circuit means is effective to arrest said first drive means in said off-normal position.

6. The combination defined in claim 5, further comprising switch means controlled by said hoist means for making said circuit means ineffectual to arrest said first drive means upon a raising of said brush above a predetermined level.

7. The combination defined in claim 1 wherein said biasing means comprises a counterweight partly balancing the weight of said brush.
